US00D959552S

(12) **United States Design Patent** (10) **Patent No.:** **US D959,552 S**
(45) **Date of Patent:** **** Aug. 2, 2022**

(54) **DISPLAY SIGN**

(71) Applicant: **Speedfind, Inc.**, Newport Beach, CA (US)

(72) Inventor: **S. Lee Hancock**, Newport Beach, CA (US)

(73) Assignee: **Speedfind, Inc.**, Newport Beach, CA (US)

(**) Term: **15 Years**

(21) Appl. No.: **29/788,716**

(22) Filed: **Jul. 21, 2021**

(51) **LOC (13) Cl.** **20-02**

(52) **U.S. Cl.**

USPC **D20/42**; D20/10; D20/40

(58) **Field of Classification Search**

USPC D3/201, 207, 208, 215, 218, 212; D10/104.1, 106.9, 106.92; D14/489; D20/10, 11, 15, 18, 19, 21, 27, 28, 29, D20/39, 40, 42

CPC G09F 27/007; G09F 21/042; G09F 13/08; G09F 21/041; G09F 7/06; B60Q 1/2615; B60Q 7/00; B60Q 1/2696; B60Q 1/2611

See application file for complete search history.

(57) **CLAIM**

The ornamental design for a display sign, as shown and described.

DESCRIPTION

FIG. 1 is a perspective view of a first embodiment of a display sign of my design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof.

FIG. 8 is a perspective view of a second embodiment of a display sign of my design;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

All broken lines illustrate portions of the article that form no part of the claimed design.

1 Claim, 8 Drawing Sheets
